U.S. CL. D55—1 C

FIG. 1

FIG. 2

FIG. 3

FIG. 4

FIG. 1 is a top plan view of the poultry feeder chain idler embodying my new design.

FIG. 2 is a peripheral view of the poultry feeder chain idler, the design shown being symmetrically repeated about the periphery and on the hidden side.

FIG. 3 is a sectional view of the poultry feeder chain idler shown in FIGS. 1 and 2, taken on line 3-3 of FIG. 1.

FIG. 4 is a bottom plan view of the poultry feeder chain idler shown in FIGS. 1, 2, and 3.

The broken line showing of the feeder chain in FIGS. 1, 3, and 4 is to illustrate the environment of the claimed design.

This application is a division of my copending application Ser. No. 271,819, filed July 14, 1972, now abandoned, and entitled Feed Chain Idler and Coupling Corner.

I claim:

The ornamental design for a poultry feeder chain idler, as shown and described.
